[57] CLAIM

The ornamental design for scissors, as shown and described.

DESCRIPTION

FIG. 1 is a plan view of a front side of scissors showing my design;

FIG. 2 is a right side elevational view of the scissors of FIG. 1;

FIG. 3 is a left side elevational view of the scissors of FIG. 1;

FIG. 4 is a front view taken in a direction viewed towards the tips of the blades of the scissors of FIG. 1; FIG. 5 is a rear view taken in a direction viewed towards the handles of the scissors of FIG. 1;

FIG. 6 is a plan view of the other or rear side of the scissors of FIG. 1;

FIG. 7 is a side elevational view of the right handle portion viewed along the lines 7—7 of FIG. 6 with the rear portion of the blade being broken off for clarity;

FIG. 8 is a side elevational view of the left handle portion viewed along the lines 8—8 of FIG. 6 with the rear portion of the blade being broken off for clarity of illustration.

FIG. 5

FIG. 6

FIG. 7

7 → 8
